G. Feightner,

Making Fifth Wheels,

No 76,899-

Patented Apr. 21, 1868.

Atty.

United States Patent Office.

GEORGE FEIGHTNER, OF WOOSTER, OHIO.

Letters Patent No. 76,899, dated April 21, 1868.

IMPROVEMENT IN MACHINE FOR FORMING FIFTH-WHEEL.

The Schedule referred to in these Letters Patent and making part of the same.

TO ALL WHOM IT MAY CONCERN:

Be it known that I, GEORGE FEIGHTNER, of Wooster, in the county of Wayne, and State of Ohio, have invented certain new and useful Improvements in Formers for Fifth-Wheels; and I do hereby declare that the following is a full, clear, and exact description thereof, reference being had to the accompanying drawings, and to the letters of reference marked thereon, which form a part of this specification, in which—

Figure 1 represents a plan, and

Figure 2 a side elevation of my invention, and

Figure 3 a side elevation of the wrench.

The object of my invention is the construction of a machine for forming the fifth wheel for wheel-vehicles, in the manner hereinafter described.

To enable others skilled in the art to make and employ my invention, I will now describe its construction and operation.

A represents a circular metal platform, placed in a horizontal position, with a projection, e, the object of which will be hereafter described. In the centre of A is a vertical post, B, say six inches in diameter. C designates a small circular platform, raised sufficiently high above platform A to correspond with the iron which is to be bent. The post B occupies the centre of said platform C. D D represent two rings, at suitable distances apart, the inner ring being separated at a proper distance from the periphery of the outer ring D. E represents a cam-lever, having at its fulcrum a bolt that passes through a slot in e. The said bolt is adjustable in the slot by means of a nut at one end. By this arrangement, the lever E can be moved in the direction of the centre of platform A, or further from the centre, as the case may require. F represents an adjustable horizontal slotted brace, which works near the top of post B. G G designate two vertical screws, one of which works in each of the slots in brace F. Each of screws G is furnished with a nut, h, the said nuts each having two wings, which are made slightly convex at their upper surface. On these wings the brace F will rest when the screws G are in position. I represents the cranks, attached to the opposite ends of screws G G, for operating them. H represents a wrench, the design of which is to form the wheel, as hereafter described. The rings D D, it will be remarked, are adjustable.

As there will necessarily be a pressure on rings D D while bending a fifth-wheel, they will be strengthened on their inner side by other rings of about half their elevation.

In operating my machine, the iron to be bent will be heated to a white heat, then fastened at its end edge-wise, by means of lever E, and also gripped and held down by a pair of blacksmith's tongs, and while thus held, the wrench H will be used to form the wheel, the inner jaw or prong of said wrench being made to rest against the side of the inner ring, D, and the outer jaw against the iron, so as to press it against the outer ring at every point, until the iron is reduced to its proper shape, or, in other words, until the fifth-wheel is completed. The screws G G will be used to hold the bent part of the iron in position until the wheel is completely formed.

Having thus described my invention, what I claim as new, and desire to secure by Letters Patent, is—

1. The removable rings D D, in combination with the platform A and adjustable cam-lever E, substantially as and for the purpose set forth.
2. In combination with the above, I claim the slotted brace F and screws G G, when used as set forth, for the purpose of retaining the fifth-wheel in place while undergoing its formation.

In testimony that I claim the foregoing as my own, I affix my signature in presence of two witnesses.

Witnesses:

HENRY LEAMAN,
A. E. LEHMAN.

GEORGE FEIGHTNER.
